UNITED STATES PATENT OFFICE.

MARION A. ESTY, OF ELDON, MISSOURI.

ROAD MACHINE.

1,420,981.

Specification of Letters Patent. Patented June 27, 1922.

Application filed January 21, 1921. Serial No. 439,039.

To all whom it may concern:

Be it known that I, MARION A. ESTY, a citizen of the United States, and resident of the city of Eldon, county of Miller, and 5 State of Missouri, have invented certain new and useful Improvements in Road Machines, of which the following is a specification containing a full, clear, and exact description, reference being had to the accompanying 10 drawings, forming a part hereof.

My invention relates to improvements in road machines, and has for its primary object a machine which may be reversed or operated in one direction for grading and 15 crowning the road bed and may be operated in a reverse direction for smoothing and packing the same.

In the drawings—

Fig. 1 is a top plan view of my machine 20 set for grading and crowning the road bed;

Fig. 2 is a side view;

Fig. 3 is an enlarged rear view with parts 25 broken away, showing the means employed for adjusting the scraper and packing blades;

Fig. 4 is a section taken on the line 4—4 of Fig. 2, looking in the direction of the arrows;

Fig. 5 is a sectional view taken on line 30 5—5 of Fig. 3, looking in the direction of the arrows in Fig. 3;

Fig. 6 is a sectional view taken on line 6—6 of Fig. 3 looking in the direction of the lowermost arrows in Fig. 3; and

Fig. 7 is a fragmental view of one of the 35 scraper blades with the plowing attachment secured to the forward end thereof.

Referring by numerals to the accompanying drawings:

7 indicates the scraper blades, which are 40 made in two sections, 8 and 9. The sections 8 are provided with horizontal flanges 10 and the sections 9 with horizontal flanges 11. These flanges are secured together by

means of rivets or bolts 12. The sections 45 9, as will be observed from Fig. 3, are curved inwardly and are sharpened along their lower edges. The sections 8 and 9, when secured together, form a very strong grading 50 blade, one blade being disposed on each side of the machine, and are pivoted together at their rear ends, as illustrated in Figs. 1 and 3. Secured to each complete blade at their rear ends are plates 13, which are disposed at the lower portions of the sections 9,

and at the upper portions of the sections 8 straps or plates 14 are secured which are provided with elongated slots 15.

The straps 13 and 14 are pivotally connected together by means of a bolt 16 provided with a nut 17. By means of the slots 15 formed in the plates 14 the scraper blades may be inclined relative to the vertical. This adjustment is made possible by the sliding connection between the straps 14 arranged along the upper portion of the blades, and the fixed connection between the straps 13 arranged along the lower portions,—thus permitting the upper portions only to be moved toward and from each other.

Mounted on the rear ends of the scraper blades are bearings 18, in which are mounted rotating shafts 19, and mounted on the upper ends of said shafts are pivotally mounted internal screw-threaded bearings 20, in which are mounted a screw-threaded shaft 21 on which there is mounted an operating wheel 22. By rotating the shaft 21 the scraper plates may be inclined relative to the vertical. This adjustment is made possible by reason of the sliding connection between the straps 14 at the upper portion of the blades, and the fixed connection between the straps 13 of the lower portion,—thus permitting the upper portions only to be adjusted toward and from each other.

Secured to the scraper plates are bearing frames 23, and mounted therein are worm screws 24 provided with an operating handle 90 25. These are adapted to engage with threads formed on the shafts 26 on which are mounted wheels 27. By the operation of the work gears 24 the wheels may be moved upwardly and downwardly, and each one of 95 the wheels may be adjusted upwardly and downwardly independent of the others. By this means the scraper blades may be inclined towards the horizontal, as desired.

Adjustably connected to the scraper blades 100 are chains 28, which pass around chain wheels 29 carried by a frame 30. Secured to the frame 30 are chains 31, which are adapted to be connected to the tractor or other motive power. Mounted on the frame 30 is 105 the shaft 32, provided with worms 33, which are adapted to engage with worm gears 34. 35 indicates a bevel gear adapted to mesh with the bevel gear 36. The bevel gear 35 is operated by a wheel 37. By rotating this 110

wheel the shaft 32 may be rotated and by the rotation of the shaft 32 the gears 34 are rotated, and consequently the chain wheels 29. By means of the wheel 37 and the wheel 22, the scraper blades may be adjusted at the forward portion to and from each other, and the rear portion of the blades may be inclined. Of course it is obvious that in adjusting the forward portions of the blades 10 relative to the horizontal to and from each other, which is made possible by the sliding connection between the blades 14, that the rear ends must also be simultaneously similarly adjusted by means of the wheel 22; 15 that is to say, if it is desired to move the blades toward each other at their front ends, as illustrated in Fig. 1, it will be necessary to operate the wheel 22 so as to permit the screw-threaded bearings 20 to move away 20 from each other.

As constructed it requires two operators to adjust the machine, one for operating the wheel 37 and the other the wheel 22.

The machine is set in Fig. 1 (in solid 25 lines) for grading and crowning the road bed, and if it is desired to smooth and pack the same, the chains by means of which the machine is pulled are attached as shown in dotted lines in Fig. 1 and the machine is 30 operated by being pulled forward in a direction toward the pivoted end of the machine. The shape of the blades being curved, as stated, they will ride over the bed and smooth and pack it down.

35 In Fig. 7 I have shown a plowing attachment which I may employ, when desired, for plowing the surface. This attachment consists of a plow 38 which is secured at the forward end of one of the scraper blades by 40 means of bolts 39. Hinges are secured to the plow 38 and the bar 40, which may be adjusted laterally, as desired, and in order to effect this adjustment I mount a cog wheel 41 in the member 42 which is bolted 45 to the flanges 10 and 11 by means of bolts 43. This gear wheel 41 is operated by means of a wheel 44. The gear wheel 41 is adapted to mesh with the rack 45, one end of which is pivotally secured to the bar 40. The rack 50 45 is held in engagement with the gear wheel 41 by means of a coil spring 46. When this plowing adjustment is secured to one of the scraper blades it is designed to throw the dirt inwardly. This adjustment 55 is especially desirable where it is necessary to plow along the side margins of a graded road surface. The bar 40 is held in the desired adjustment by means of a removable pin 47 located in suitable holes formed in 60 the member 42. This pin is adapted to be inserted between the teeth formed on the gear wheel 41.

Having fully described my invention, what I claim is:

1. A road machine composed of two 65 scraper and packing blades pivotally connected together, means located at the rear end of the blades for inclining the same and means for adjusting the blades to and from each other while the machine is in motion, 70 and adjustable wheel supports for said blades, said blades being arranged to grade the road surface and crown it when moving in one direction and when moving in the opposite direction to pack and smooth said 75 surface.

2. A road machine composed of two blades pivoted together at their rear ends, said pivotal connection permitting the blades to be inclined by adjusting only the upper portions thereof to and from each other, a pivoted screw-threaded bearing carried by the rear ends of each blade, a screw-threaded shaft provided with an operating wheel mounted in said bearings, a flexible connection secured to said blades, a frame operatively connected to said flexible connections, a shaft and work gear and operating wheel for operating said flexible connections, and chains secured to said frame and adapted to 85 be connected to any suitable motive power. 90

3. A road machine composed of two scraper and packing blades, means for pivotally securing the forward ends of said blades together, a vertical shaft pivotally 95 carried by the forward end of each blade, a pivoted internally screw-threaded bearing carried by each shaft, a screw threaded shaft mounted in said bearings, a wheel mounted on said shaft for operating the 100 same whereby the blades may be inclined, means for adjusting said blades relative to the horizontal, flexible connections secured to said blades, a frame having chain wheels around which flexible connections pass, and 105 a shaft provided with worm gears for rotating said chain wheels for adjusting the blades toward each other.

4. In a road machine a scraping and packing blade formed of two sections, the adjacent edges of the sections being provided with right angular projecting flanges, bolts passing through said flanges for securing the sections together, one of said sections being provided with a transversely curved surface 115 which may be employed when operated in one direction for scraping the road, and when operated in the opposite direction for packing the road, and means carried by the rear end of the blade for adjusting only the 120 upper portion thereof so as to incline the blade.

M. A. ESTY.
